US00D900595S

(12) **United States Design Patent** (10) Patent No.: **US D900,595 S**
(45) Date of Patent: **** Nov. 3, 2020**

(54) **FASTENING, SUPPORTING OR MOUNTING DEVICE**

(71) Applicant: **Pflitsch GmbH & Co. KG**,
Huckeswagen (DE)

(72) Inventor: **Roland Schmitz**, Wipperfurth (DE)

(73) Assignee: **Pflitsch GmbH & Co. KG**,
Huckeswagen (DE)

(**) Term: **15 Years**

(21) Appl. No.: **35/507,162**

(22) Filed: **Feb. 1, 2019**

(80) **Hague Agreement Data**

Int. Filing Date: **Feb. 1, 2019**

Int. Reg. No.: **DM/201211**

Int. Reg. Date: **Feb. 1, 2019**

Int. Reg. Pub. Date: **Aug. 2, 2019**

(51) **LOC (12) Cl. 08-05**

(52) **U.S. Cl.**

USPC **D8/354**

(58) **Field of Classification Search**

USPC D8/16, 353, 354, 366, 499

CPC . H02G 3/125; F16B 45/00; A45F 5/00; A45F 2005/002

(57) **CLAIM**

The ornamental design for fastening, supporting or mounting device, as shown and described.

DESCRIPTION

Design No./Product(s):

1.-2. Fastening, supporting or mounting device

Description of the Reproduction(s):

1.1 : Top

1.2 : Right

1.3 : Bottom

1.4 : Perspective

1.5 : Back

1.6 : Front

1.7 : Left

5.1 : Bottom

5.2 : Top

5.3 : Back

5.4 : Perspective

5.5 : Front

5.6 : Right
